UNITED STATES PATENT OFFICE.

UEL REYNOLDS, OF NEW YORK, N. Y.

IMPROVEMENT IN BODY-TOPS FOR CARRIAGES.

Specification forming part of Letters Patent No. 58,292, dated September 25, 1866.

To all whom it may concern:

Be it known that I, UEL REYNOLDS, of the city and State of New York, have invented, made, and applied to use, a certain new and useful Improvement in Body-Loops for Carriages, &c.; and I do hereby declare the following to be a full, clear, and exact description of the said invention, reference being had to the annexed drawings, making part of this specification, wherein—

Figure 1 is a side view of the body-loop applied to the end of the spring-bar, and Fig. 2 represents a portion of the end of the spring-bar with the body-loop attached.

Similar letters refer to the same parts.

It has been usual heretofore to rest the end of the body-loop upon the spring-bar, and attach the same by a bolt passing through the said body-loop and the wooden spring-bar. This greatly weakens the spring-bar and renders it liable to split, particularly in light carriages, when the wooden spring-bar is small.

The nature of my said invention consists in a clip body-loop, the same being a new article of manufacture, formed as a metal loop extending from the under side of the carriage-body to the upper side of the spring-bar, and to which it is attached by a clip, formed at the end of said metal body-loop, so that the wooden spring-bar is not injured or weakened by being perforated.

In the drawings, *a* represents a portion of the

wooden spring-bar; *b*, a portion of the corner of the carriage-body. *c* is the metal body-loop, formed as a strap attached to the under side of the body at the corner and extending out over the wooden spring-bar *a*.

d is the clip formed at the end of the body-loop *c*, to surround said wooden spring-bar *a*, and be firmly attached thereto by the clamping action of the nuts *e e*.

It will be evident that the clip-part *d* might be inverted, the nuts *e e* being above the body-loop *c*, the clip being formed as a strap passing below the end of the spring-bar *a*, and the body-loop having holes through which the ends of the clip pass to the nuts above said body-loop.

I do not claim attaching a spring to the spring-bar by means of a clip, as that has before been done. My body-loop is not a spring; it only forms a rigid attachment between the corners of the carriage and the spring-bar, and is a new article of manufacture.

What I claim, and desire to secure by Letters Patent, is—

The clip body-loop constructed as and for the purposes specified.

In witness whereof I have hereunto set my signature this 5th day of March, 1866.

UEL REYNOLDS.
